UNITED STATES PATENT OFFICE.

LEO PERZIN, OF PHILADELPHIA, PENNSYLVANIA.

ARTIFICIAL TOOTH.

1,071,952.

Specification of Letters Patent.

Patented Sept. 3, 1913.

Application filed October 19, 1912. Serial No. 726,686.

To all whom it may concern:

Be it known that I, LEO PERZIN, a subject of the Czar of Russia, and a resident of Philadelphia, Pennsylvania, have invented 5 certain new and useful Improvements in Artificial Teeth, of which the following is a specification.

The purpose of my invention is to protect the hollow pins in porcelain teeth from 10 filling with wax during the process of carding for exhibit and sale and to enable these tubular attaching means or pins to be forced through gold backings secured to the inner surface of the porcelain.

15 Figure 1 is a perspective view, showing a number of teeth carded for sale. Fig. 2 is a longitudinal section of a tooth with a pin in place. Fig. 3 is an elevation partly in section of a card having a tooth mounted 20 thereon. Figs. 4-6 are longitudinal cross sectional views illustrating my invention.

In the construction of artificial tooth facings, it has been found advantageous to attach these facings or "teeth" to a gold back- 25 ing material by pins having tubular ends projecting beyond the surface of the porcelain so that these tubular projecting ends may be passed through the backing and turned outwardly and rearwardly, as in the 30 case of eyelet setting, and thus retain the backing rigidly against the facing. These tubular pins must stand the baking heat of porcelain and are commonly made of platinum, consequently very expensive. In order 35 to prevent intrusion of the wax within the tubular end of the pins when carded as seen in Fig. 1 and at the same time facilitate the insertion of the pins through metal backings, such as are shown in Figs. 4 and 6, I 40 have provided a pointed plug which I temporarily insert within the tubular pin. I prefer to use a pin which is tubular throughout its length, because it is cheaper and gives a longer bearing for the pointed plug 45 and because I am enabled readily to swell it at the end within the porcelain for anchorage purposes.

I have accomplished the double purpose 50 of preventing the wax of the card mount from being forced into the tubular pins and of preparing the pins for making their own holes within the backing without preliminary measurements by providing pointed

inserts of baser metal for the ends of these tubular pins. Within the tooth body 1, I 55 have placed a tube 2 of infusible material, preferably platinum, which I have belled or flared at the end, as at 3, in order that it may be thoroughly anchored therein, leaving the entire interior of the pin open, as at 60 4, and of substantially uniform diameter throughout the outer portion thereof, for the double purpose of saving platinum and providing for rigid side support of my plug 5. This plug prevents the wax or other material of the card mount 7 from being forced 65 within the opening 4 of the pins. The plugs may be removed for subsequent finish of the pins by bending or turning at 8, as in Fig. 6, or may be soldered tightly therein if desired. This latter stiffens the pin with a much less expensive metal than the platinum and permits the use of the projecting plug with shorter tubular pins, than would otherwise be required, since the tubular 70 platinum need then not extend beyond the porcelain.

In order to facilitate the placing of the facings upon the backings 6, without the necessity for preliminary measurement, I point 80 the plugs 5, as at 9, so that they will pierce the backing and guide the tubular pins through the openings thus formed.

The platinum pin, while not as soft as the 85 preferably gold backing 6, is much softer than the baser metal, which I prefer to use for the plugs 5 but, supported by such plugs, these tubular pins will readily enlarge the opening, which has been started by the plugs and pass through the back to the position 90 shown in Fig. 4. This figure illustrates my preferred construction where the tubular pin 2 is extended to pass through the backing and to be turned over, as in Fig. 6.

Having thus described my invention, what 95 I claim as new and desire to secure by Letters Patent is:

In a device of the character stated, a tooth body, a tubular pin therein, projecting beyond the surface of the tooth and a pointed 100 temporary plug for said pin, having its point projecting beyond the pin.

LEO PERZIN.
